DESIGN FOR A GLASS RELISH DISH OR ARTICLE OF SIMILAR NATURE

Albert H. Nicholson, Columbus, Ohio, assignor to The Federal Glass Company, Columbus,
Ohio, a corporation of Ohio

Application November 14, 1939, Serial No. 88,283

Term of patent 3½ years

To all whom it may concern:

Be it known that I, Albert H. Nicholson, a citizen of the United States of America, residing at Columbus, in the county of Franklin and State of Ohio, have invented a new, original, and ornamental Design for a Glass Relish Dish or Article of Similar Nature, of which the following is the specification, reference being had to the accompanying drawing, forming a part thereof.

of the glass relish dish or article of similar nature showing my new design.

I claim:

The ornamental design for a glass relish dish or article of similar nature, substantially as shown.

ALBERT H. NICHOLSON.
